(57) **CLAIM**

The ornamental design for a valve trim, as shown and described.

DESCRIPTION

FIG. 1 is a perspective view of a valve trim showing my new design;

FIG. 2 is a top plan view thereof;

FIG. 3 is a front elevational view thereof;

FIG. 4 is a left side view thereof, the opposite side being a mirror image of the side shown;

FIG. 5 is a rear view thereof; and,

FIG. 6 is a bottom view thereof.

The broken line showing a handle is included for the purpose of illustrating environment that forms no part of the claimed design.
